STOMACH IRRIGATION TUBE

Arthur L. Kaslow, Hollywood, Calif.

Application March 29, 1947, Serial No. 738,019

7 Claims. (Cl. 128—227)

1

The present invention relates generally to devices professionally referred to as gastro-intestinal tubes which are arranged for insertion through the mouth or nasal passages and esophagus into the stomach or other portion of the intestinal tract for diagnostic purposes or passing of liquids for lavaging or feeding a patient.

It has heretofore been common practice to utilize a single lumen tube and a syringe connected thereto, for example, in lavaging the stomach of a patient. The syringe is filled with clean liquid which is forced into the stomach and thereafter sucked out by reverse operation of the syringe. The syringe must be then disconnected, emptied, and refilled with clean liquid before the process can again be repeated. The operation is therefore one which is inconvenient to accomplish with a single lumen tube and also is inherently undesirable due to the fact that the syringe tends to squirt the liquid with such force that the membranes lining the stomach may become irritated.

In its broad concept, my present invention contemplates a double-lumen tube which is so arranged that the fluids may be gradually admitted into the stomach and continuously circulated without causing irritation and discomfort to the patient. Moreover, when utilizing the device of my invention for the feeding of fluids directly into the stomach, this feeding may be accomplished at a gradual admission rate so that the foods are absorbed without being caused to accumulate and cause distension and possible vomiting. My improved construction further enables my improved device to be utilized for a multiplicity of purposes, for which the single lumen tube is ill adapted.

Having the foregoing in mind, it is a primary object of the present invention to provide an improved device of the herein described type utilizing a double-lumen construction in which the lumina have separate connections at their proximal ends and separate communication openings at their distal ends, so as to enable employment of the device for a plurality of purposes; for example, the continuous circulation of a lavaging fluid; simultaneous feeding and medicating; fractional gastric analysis while administering a stimulant to increase gastric flow activity; as well as other purposes which will be apparent to those familiar with the use of such devices.

It is a further object to provide an improved device of this character in which the communicating openings at its distal end are so arranged that the possibility of their becoming blocked or

2

occluded by mucosa or otherwise is reduced to a minimum, if not entirely eliminated.

Another object is to provide an improved construction at the distal end of the device, wherein a tip is formed by a projecting looped portion of the innermost tube, this tip being non-metallic and non-traumatic, and from which there will be no danger of irritation to mucous membranes, either during intubation or during use of the device.

10 It is also an object of the invention to provide a device of this character which is constructed of a material of such nature as to permit the use of ointments for facilitating intubation and which will not deleteriously be affected thereby, as in the 15 case of previously used rubber tubes, and which may be made transparent so as to enable continuous visualization of the gastro-intestinal drainage and permit frequent changes in therapy.

Further objects of the invention will be brought 20 out in the following part of the specification, wherein detailed description is for the purpose of fully disclosing preferred embodiments of the invention without placing limitations on the scope of the invention defined in the appended claims.

25 Referring to the drawings which are for illustrative purposes only, the single figure is a fragmentary view of the device of my invention, portions being cut away and parts shown in section to more clearly disclose certain features of its 30 construction.

As specifically disclosed, the gastro-intestinal tube of my invention comprises an elongate tube 10 of smooth transparent plastic material of approximately 16 French diameter within which there is disposed an inner transparent plastic tube 35 of approximately 3 to 4 French diameter, the inner tube being indicated by the numeral 11. In general, the tubes 10 and 11 are assembled in concentric relation with the tube 11 running substantially throughout the length of the tube 10.

The entire device, for purposes of consideration, may be considered as made up of three portions, a proximal end portion, as generally indicated by the numeral 12, a distal end portion, as 45 generally indicated by the numeral 13, and an intermediate portion connecting these end portions, as generally indicated by the numeral 14.

The distal end of the tube 10 is inwardly folded upon itself as shown at 15 to provide a rounded 50 end edge 16. The associated distal end of the small or inner tube 11 is formed into a reentrant loop 17, the extreme end 18 of this tube being sealed and projecting back into the interior of the distal end of the outer tube 10. This end of the 55 tube 10 is then sealed around the small tube by

utilization of a suitable plastic solvent or other means.

The loop 17 is provided on its inside with a series of openings or fenestrations 19 so that this loop forms a tip or nozzle for the passage of fluid for purposes which will be subsequently explained more fully.

The distal end of the tube 10 is likewise provided with a plurality of openings or fenestrations as indicated by the numeral 20. In practice, these fenestrations are located in the six or seven inch end portion of the tube 10, and are positioned along a spiraled line around this end of the tube.

The construction just described is particularly advantageous in that the tip or nozzle formed by the reentrant loop 17 gives a pliable soft construction which is non-traumatic, and will not irritate the mucous membrane linings. Moreover, by placing the openings 19 on the inside of the loop portion, these openings are not easily blocked or occluded by intestinal mucosa or otherwise. During intubation or when engaging an object, this loop will act with a spreading action and tend to push the object or mucosa away, thus providing better drainage and keeping the path clear. Likewise, in the case of the openings in the tube 10, these openings by being arranged spirally around the wall of the tube are not all apt to become blocked at the same time, and in practice it has been found that a passage through a portion of the openings will be maintained at all times.

In the intermediate portion 14, the tube 10 and tube 11 are continuous. In the case of the outer or larger tube 10, a mark, as indicated at 21, is placed on the outer surface of the tube and marked or identified with the numeral 30 to indicate that this mark is thirty inches from the distal end of the device. If desired, of course, additional marks may be positioned and properly identified along the outer surface of the tube for use as a measure to indicate the amount of insertion or intubation.

The proximal end 12 may consist of a tubular extension 22 which may be of plastic, but may be of rubber. This extension is connected with one end of the tube 10 by means of a tubular connector 23 which may be of clear plastic material.

The inner tube 11 passes through the connector 23 and thereafter is carried through a slit or opening 24 in the wall of the extension 22. At the point of passage through the opening 24, the tube 11 is sealed with reference to the wall of the extension 22, so that there will be no leakage at this point. With the construction just described, it will be apparent that separate connections will be provided into the tubes 10 and 11 at the proximal end of the device.

The utilization of plastic materials in the tubes 10 and 11 is of particular advantage in that it is possible to make these tubes transparent so that a continuous visualization of the gastric-intestinal drainage is permitted and the desirability for changes in therapy determined. Moreover, the use of plastic materials not deleteriously affected by ointments which would ordinarily be injurious to rubber tubes, permits the use of these ointments for facilitating intubation with greater ease and less discomfort to the patient.

As examples of a number of uses for my improved device, it is particularly adapted for cleansing or laving of the stomach or intestinal tract and when so used, provides a continuous circulation. For such purpose, a container 25,

which may be part of a drip feed device, is connected through a hollow needle with the proximal end of the tube 11. In this case, the proximal end of the tube 10 may be connected to a suitable source of suction. With the tubes thus connected and inserted, for example, into the stomach, fluid may be gradually fed through the openings 19 of the loop 17 and extracted by the suction through the openings 20 in the distal end of the tube 10.

The device is also admirably adapted for use where it may be desired to simultaneously feed and medicate the stomach. In such case, the feeding may be accomplished through the tube 10 and medication administered through the small tube 11.

Another example of using the present device is for fractional gastric analysis, in which case, contents of the gastro-intestinal tract may be sucked through the large tube, and, if desired, a stimulant may be simultaneously administered through the small inner tube to increase the gastric flow activity.

In the case of feeding, my improved device has been found very advantageous, since it permits supplying of the liquid food at a rate sufficiently slow to permit absorption of the food without causing a distension due to accumulation. Vomiting may thus be obviated and the food administered without discomfort to the patient.

Other advantages and uses of my improved device will readily become apparent to those familiar with the use of such devices.

I claim as my invention:

1. A gastro-intestinal device comprising an outer transparent tube of plastic material, a smaller tube of transparent plastic material within the first tube, said tubes at their proximal ends having the smaller tube carried through the wall of the outer tube to effect separate connections to said tubes, and at their distal ends having the smaller tube formed into a looped portion projecting from the associated end of the outer tube and provided on the inside of the loop with a plurality of openings, the distal end portion of the outer tube being provided with a series of wall openings.

2. A gastro-intestinal device comprising an outer tube having an opening adjacent its distal end, and another tube disposed within the first tube with an end projecting from the distal end of said first tube and formed into a loop having an opening therein, said distal end being sealed with respect to the inner tube passing therethrough.

3. A gastro-intestinal device comprising an outer tube having a spiraled line of openings at its distal end, another tube disposed within the first tube with a looped end projecting from the distal end of the first tube, said looped end having an opening therein, and means sealing said distal end with respect to the innermost tube.

4. A gastro-intestinal device comprising an outer tube having a series of openings adjacent its distal end, another tube disposed within the first tube with a looped end projecting from the distal end of the first tube, said looped end having a series of openings on its inner side, and means sealing said distal end with respect to the innermost tube.

5. A gastro-intestinal device comprising an outer tube having a turned-back distal end portion, and another tube disposed within the first tube with an end projecting from said distal end, the projecting portion of the inner tube and the

adjacent portion of the distal end having wall openings therein.

6. A gastro-intestinal device comprising a pair of elongate flexible tube members in concentric relation, the innermost of said tubes projecting from an end of the outermost tube and being formed into a reentrant loop portion having a plurality of openings therein, the adjacent portion of said end of the outermost tube having openings therein, and means sealing said end with respect to the innermost tube.

7. In a device of the character described, a pair of elongate flexible tubes in co-axial relation arranged at their proximal ends for separate individual connections, the innermost of said tubes extending beyond the distal end of the outermost tube and having its distal end sealed within the distal end of the outer tube to form a projecting loop in the innermost tube adjacent the distal end of the outermost tube, said tubes having flow 20

6
openings adjacent the distal end of the outermost tube.
